UNITED STATES PATENT OFFICE.

CARL RASMUSSEN, OF BRUNSWICK, GERMANY.

CALCULATING-MACHINE.

1,100,616.

Specification of Letters Patent. Patented June 16, 1914.

Application filed February 20, 1914. Serial No. 819,978.

To all whom it may concern:

Be it known that I, CARL RASMUSSEN, engineer, subject of the King of Norway, residing at Brunswick, Germany, have invented 5 certain new and useful Improvements in Calculating-Machines, of which the following is a specification.

My invention relates to improvements in calculating machines, and more particularly in calculating machines in which the setting mechanism consists of disks provided with radially shiftable teeth representing the values to be transmitted to the registering mechanism, and cam disks coöperating with the disks and adapted to shift the desired number of teeth into operative positions. In machines of this class the registering mechanism is mounted on a laterally shiftable carriage, which also carries 10 a revolutions counting mechanism, the revolutions counting mechanism being ordinarily mounted at the left hand side of the registering mechanism. A machine of this class is shown for example in the patent of 15 the United States No. 1,040,059, dated October 1, 1912, granted to Franz Trinks.

In calculating machines which are designed for performing calculations of every kind the revolutions counting mechanism 20 must be constructed in such a way, that it can be used in a similar way as the registering mechanism, and more particularly it must be possible to operate the numeral wheels of any order. For this reason between adjacent numeral wheels of the revolutions counting mechanism sets of gear wheels have been provided for the carrying mechanism which can be rocked in radial direction. These sets of gear wheels can be 25 rocked independently of each other, and they are rocked by the operating mechanism for the carrying mechanism, which travels on the carriage from one numeral wheel to the other and is operated in such a way, that 30 during the revolution of the crank and prior to the operation of a numeral wheel of the revolutions counting mechanism the carrying mechanism which is located at the right of the said numeral wheel is thrown out of 35 operation. Mechanism of this kind is shown for example in the patent of the 40 United States No. 1,007,618, dated October

31, 1911, granted to Franz Trinks. This mechanism requires much space and it is very heavy, and furthermore the heads of the teeth of the sets of gear wheels are liable to engage the heads of the spur gears connected with the numeral wheels when the sets of gear wheels are rocked backward.

The object of the improvements is to provide a mechanism of this kind, in which the numeral wheel which is located in each case at the right of the driving mechanism is thrown out of operation by axially displacing the coöperating intermediate gear wheel. By thus constructing the mechanism the carrying mechanism is thrown out of operation in a reliable way, because the mechanism provided therefore is mounted on the same axis as the intermediate gear wheels, and the intermediate gear wheels are thrown into operation by the moving tooth controlling the same, before advancing the same.

For the purpose of explaining the invention an example embodying the same has been shown in the accompanying drawings, in which the same letters of reference have been used in all the views to indicate corresponding parts.

In said drawings—Figure 1, is a front view of the calculating machine partly in section and with the cover of the casing partly removed and showing the carriage in the normal position. Fig. 2, is a cross-section of the machine taken on the line 2—2 of Fig. 1, and Fig. 3, is a front view similar to that shown in Fig. 1 and illustrating a part of the revolutions counting mechanism the carriage of which has been shifted a distance corresponding to one order.

In the example shown in the drawings a calculating machine has been shown in which the revolutions counting mechanism is located at the left of the registering mechanism and on a carriage which is shiftable in a direction parallel to the axis of the setting disks, the revolutions counting mechanism being shiftable relatively to a non-shiftable single tooth provided for operating the same.

The setting mechanism consists of setting disks which are mounted on a shaft c adapted to be rotated from a crank c^3 by means of gear wheels c^1 and c^2 . The setting

disks are provided with radially shiftable teeth which are adapted to be shifted in radial direction by means of cam disks projecting with handles e through slits j^1 made 5 in the cover of the casing. When rotating the crank c^3 the values set on the setting disks and represented by the shifted teeth are transmitted to numeral wheels l , which provide the registering mechanism and are 10 mounted on a carriage q which is shiftable in a direction parallel to the axis e of the setting disks. For resetting the registering mechanism a wing nut u is provided. At the left of the registering mechanism l 15 a revolutions counting mechanism is mounted on the carriage q , which registers the number of the revolutions of the crank c^3 on numeral wheels. My invention relates more particularly to this revolutions counting mechanism.

Each of the numeral disks a of the revolutions counting mechanism is provided at its right hand face with a gear wheel b provided with ten teeth. At the left hand face 25 each of the said disks is provided with a flange b' formed with a single tooth b'' . All the disks are loosely mounted together with their gearings on a shaft d which is also used for resetting the revolutions counting 30 mechanism and is provided for this purpose with a wing nut d' , as is shown in Fig. 1.

On the carriage q a shaft g is fixed on which intermediate gear wheels h are loosely mounted, which are in mesh with the gear 35 wheels b , and at the right of each of the intermediate gear wheels h levers i are supported which are adapted to be rocked on the said axis at a certain angle. The hubs of the levers are formed with notches i' the 40 side walls of which are beveled to opposite sides. The said notches are engaged by noses k' of disks k which are formed accordingly. The disks are provided at both sides of the levers i with arms k'' and they are 45 rigidly secured to the stationary axis g . The arms k'' project into the plane through which the levers i are moved, and they limit the rocking movements of the latter in both directions.

50 Between each of the disks k and the adjacent intermediate gear wheel h there is a spring f which has the tendency to force the co-operating intermediate gear wheel h and the hub of the adjacent rocking lever i against the disk k and with the nose k' in engagement with the co-operating notch i' .

In the relative position of the parts k' and i' shown in the drawings the lever i is 55 in the middle between the stop arms k'' , as is shown in Fig. 2. The breadth of the intermediate gear wheel h is such, that its teeth are disposed in the plane of the gear wheel b as well as in that of the single tooth

b'' of the numeral disk a of the next lower order, as is best shown in Fig. 1.

On a stationary pivot m a gear wheel r is mounted which forms a part of a reversing gearing to be described hereinafter, and which is adapted to be rotated either to the right or to the left from the resetting shaft c by means of intermediate gear wheels v , v' , v^2 . The gear wheel r is connected with a lever o providing a single tooth, which carries an arc shaped member o' directed 75 from the single tooth to opposite sides and disposed in the plane of the lever i .

If the carriage q is in the normal position shown in Fig. 1, and the crank c^3 is turned, the single tooth o engages the first 80 one of the intermediate gear wheels h which is located in Fig. 1 at the right hand end of the revolutions counting mechanism. Thereby the revolutions counting mechanism is advanced a distance corresponding to one 85 value, as is known in the art. If the carriage is shifted to the right, for example the distance of two adjacent numeral wheels and into the position shown in Fig. 3 in which the single tooth o co-operates with a 90 numeral wheel of a higher order, and if now the crank of the machine is turned, at first the corresponding end of the arc shaped member o' engages the lever i which is located in the path of the said member, and 95 rocks the same so far that the notch i' rises on the beveled nose k' of the disk k . Thereby the co-operating intermediate gear wheel h is shifted to the left and out of the 100 plane of the tooth b' , so that it is in engagement only with the gear wheel b . Therefore the single tooth o has no effect on the disks a of the revolutions counting mechanism which are located at the right thereof, and as it passes the intermediate gear wheel, 105 only the disk which is located at the left is advanced.

The advancing movement is transmitted to the left hand part of the revolutions counting mechanism, because the intermediate gear wheels are in such positions, that they are in the paths of the single teeth b'' as well as in the plane of the gear wheels b of the next following numeral wheel.

The length of the arc shaped member o' 115 and the relative distance of the stationary stops k'' are such that when rocking the lever i the notches are not perfectly disengaged from the noses k' , so that after the tooth o has been disengaged from the co-operating intermediate gear wheel h the lever i is returned by the spring f into initial position in which it is at the middle between the stops k'' .

In order that with the same direction of 125 rotation of the main shaft n which carries the setting disks and the shiftable teeth the tooth o can be rotated either to the right

or to the left, a gear wheel p is provided on the shaft n , which is longitudinally shiftable thereon and is adapted to be rotated from the main shaft by the intermediate gear wheels v , v^1 , v^2 , and the said gear wheel is in engagement according to its position either with the broad spur gearing r mounted on the shaft m or with the reversing gearings s . The latter has likewise a considerable breadth and is always in mesh with the spur gearing r . If the gear wheel p is shifted by means of a sliding rod t from the position shown in Fig. 1 to the left and out of engagement with the spur gearing r , the said gearing r is rotated through the intermediary of the reversing gearing s , so that it rotates in the opposite direction.

As compared to change or reversing gearings of known construction the one shown herein is preferable, because the three gear wheels p , r , and s are always rotating for both directions of rotation, the gear wheel s running idle and the gear wheels p and r transmitting the movement of the shaft n to the single tooth o , if the gearing is rotating in one direction. If the gear wheel p is shifted relatively to the gear wheel s , the latter transmits the rotation to the single tooth o .

By reason of this construction the direction of rotation can at any time be reversed without interfering with the proper function of the mechanism.

I claim herein as my invention:

1. In a calculating machine, the combination with the rotary setting mechanism, and a registering mechanism coöperating therewith, said setting mechanism and registering mechanism being shiftable relatively to each other, of revolutions counting mechanism comprising numeral wheels and axially shiftable intermediate gear wheels connected with the registering mechanism and an operating member connected with the setting mechanism and non-shiftable relatively thereto, operating gearings provided respectively on opposite sides of said numeral wheels of the revolutions counting mechanism, the gearings located at the side of the higher order being operative during a part of their revolution only and gearings of adjacent numeral wheels being located in positions for engagement with the same intermediate gear wheel, means operative prior to the engagement of an intermediate gear wheel with the operating member to shift the intermediate gear wheel out of engagement with the coöperating gearing which is operative during a part of its revolution, and automatic means to return the intermediate gear wheel into normal position.

2. In a calculating machine, the combination with the rotary setting mechanism,

and a registering mechanism coöperating therewith, said setting mechanism and registering mechanism being shiftable relatively to each other, of revolutions counting mechanism comprising numeral wheels and axially shiftable intermediate gear wheels connected with the registering mechanism and an operating member connected with the setting mechanism and non-shiftable relatively thereto, operating gearings provided respectively on opposite sides of said numeral wheels of the revolutions counting mechanism, the gearings located at the side of the higher order being operative during a part of their revolution only and gearings of adjacent numeral wheels being located in positions for engagement with the same intermediate gear wheel, means connected with the operating member and operative prior to the engagement of an intermediate gear wheel with the operating member to shift the intermediate gear wheel out of engagement with the coöperating gearing which is operative during a part of its revolution, and automatic means to return the intermediate gear wheel into normal position.

3. In a calculating machine, the combination with the rotary setting mechanism, and a registering mechanism coöperating therewith, said setting mechanism and registering mechanism being shiftable relatively to each other, of revolutions counting mechanism comprising numeral wheels and axially shiftable intermediate gear wheels connected with the registering mechanism and an operating member connected with the setting mechanism and non-shiftable relatively thereto, operating gearings provided respectively on opposite sides of said numeral wheels of the revolutions counting mechanism, the gearings located at the side of the higher order being operative during a part of their revolution only and gearings of adjacent numeral wheels being located in positions for engagement with the same intermediate gear wheel, sets of rocking and stationary cam members coöperating one with each of the intermediate gear wheels and adapted to shift the intermediate gear wheel coöperating with said operating member out of engagement with the coöperating gearing which is operative during a part of its revolution, means operative prior to the engagement of the operating member with the intermediate gear wheel to rock the coöperating rocking cam member, and automatic means to return the rocking member into normal position.

4. In a calculating machine, the combination with the rotary setting mechanism, and a registering mechanism coöperating therewith, said setting mechanism and registering mechanism being shiftable relatively to each

- other, of revolutions counting mechanism comprising numeral wheels and axially shiftable intermediate gear wheels connected with the registering mechanism and an operating member connected with the setting mechanism and non-shiftable relatively thereto, operating gearings provided respectively on opposite sides of said numeral wheels of the revolutions counting mechanism, the gearings located at the side of the higher order being operative during a part of their revolution only and gearings of adjacent numeral wheels being located in positions for engagement with the same intermediate gear wheel, sets of rocking and stationary cam members coöperating one with each of the intermediate gear wheels and adapted to shift the intermediate gear wheel coöperating with said operating member out of engagement with the coöperating gearing which is operative during a part of its revolution, means connected with the operating member and operative prior to the engagement of the operating member with the intermediate gear wheel to rock the coöperating rocking cam member, and automatic means to return the rocking member into normal position.
5. In a calculating machine, the combination with the rotary setting mechanism, and a registering mechanism coöperating therewith, said setting mechanism and registering mechanism being shiftable relatively to each other, of revolutions counting mechanism comprising numeral wheels and axially shiftable intermediate gear wheels connected with the registering mechanism and an operating member connected with the setting mechanism and non-shiftable relatively thereto, operating gearings provided respectively on opposite sides of said numeral wheels of the revolutions counting mechanism, the gearings located at the side of the higher order being operative during a part of their revolution only and gearings of adjacent numeral wheels being located in positions for engagement with the same intermediate gear wheel, sets of rocking and stationary cam members and springs coöperating one with each of the intermediate gear wheels and adapted to shift the intermediate gear wheel coöperating with said operating member respectively into engagement with the coöperating gearing which is operative during a part of its revolution, stop members adapted to arrest said rocking cam members in positions in which they are adapted to be returned by the springs into normal positions, and means operative prior to the engagement of the operating member with the intermediate gear wheel to rock the coöperating rocking cam member.
7. In a calculating machine, the combination with the rotary setting mechanism, and a registering mechanism coöperating therewith, said setting mechanism and registering mechanism being shiftable relatively to each other, of revolutions counting mechanism comprising numeral wheels and axially shiftable intermediate gear wheels connected with the registering mechanism, an operating member connected with the setting mechanism and non-shiftable relatively thereto and a reversing gearing intermediate said setting mechanism and operating member, said reversing gearing comprising a driven gear wheel, an intermediate gear wheel in mesh with the driven gear wheel, a driving gear wheel, and means to set said driving gear wheel in position for engagement with the driven gear wheel and out of engagement with the intermediate gear wheel and in position for engagement with the intermediate gear wheel and out of engagement with the driven gear wheel, operating gearings provided respectively on opposite sides of said numeral wheels of the revolutions counting mechanism, the gearings located at the side of the higher order being operative during a part of their revolution only and gearings of adjacent numeral wheels being located in positions for engagement with the same intermediate gear wheel, means operative prior to the engagement of an intermediate gear wheel with the operating
